UNITED STATES PATENT OFFICE.

WILLIAM GIBSON, OF BELFAST, IRELAND.

RING-SPINNING APPARATUS.

1,333,169.

Specification of Letters Patent.

Patented Mar. 9, 1920.

Application filed October 29, 1918. Serial No. 260,191.

To all whom it may concern:

Be it known that I, WILLIAM GIBSON, a subject of the King of Great Britain and Ireland, residing at Belfast, Ireland, have 5 invented certain new and useful Improvements Relating to Ring-Spinning Apparatus, of which the following is a specification.

This invention relates to apparatus for 10 the wet or dry spinning of fibers, such for example as flax or cotton fibers, of the class having a movable ring capable, under the action of the yarn, of rolling eccentrically in a groove in the fixed ring or ring-plate 15 and its object is to improve the construction of such apparatus.

Under my invention, I provide a fixed member or ring which serves as an anti-balloonning device and also acts as an automatic 20 drag on the yarn. The fixed member or ring, which co-acts with the ring plate or builder plate to form the annular groove for the usual movable ring, is so shaped as hereinafter described that there can be, practically, no accumulation of gummy or wet 25 deposit from the yarn near its inner surface or near the space between the anti-balloonning ring and the movable ring, thereby keeping the thread path free from dirt. The 30 anti-balloonning ring or member has a slit in it which facilitates the easy laying and piecing of the yarn these operations being also assisted by the provision of a disk on the spindle, or turning therewith, having a slit 35 or slits therein for holding the yarn in such manner that the thread may be laid on without stopping the spindle.

In order that the invention may be clearly understood I have hereunto appended an 40 explanatory sheet of drawings, whereon:

Figure 1 shows the device with an empty bobbin on the spindle and the thread in position when starting to spin.

Fig. 2 shows the bobbin filled and the 45 builder plate in its top position ready for doffing.

Fig. 3 is a plan view corresponding to Fig. 1.

Fig. 4 is a plan view corresponding to 50 Fig. 2.

Fig. 5 is an enlarged detail view of the slotted portion of the anti-balloonning ring and the builder plate showing the shape of the slit at top and bottom which allows for 55 the spinning spindle being rotated right or left as desired while it insures that the yarn

will not, accidentally, enter the slit in the ring.

Referring to the drawings:

a is the spinning spindle, *b* the bobbin, *c* 60 the builder plate and *d* the movable ring.

The movable ring is accommodated in an annular recess *d*¹ formed by, or between, the ring *f* and the builder plate *c*. The ring *f* is extended upward to form the anti-balloonning ring *f*¹ whose inner wall or surface *f*² also acts as an automatic drag on the yarn. The surface *f*² may be plain or covered with suitable material to give the required dragging effect on and (or) polish to 70 the yarn. The outer side *f*³ of the ring *f* is sloped, as shown, to give a top edge *f*⁴ of the least possible thickness so that the gummy and wet deposit from the yarn will gravitate 75 down the slope to the bottom of the ring *f*¹ thereby keeping the thread path free from dirt and this may be further insured by the movable drag ring *d* being within the recess *d*¹ where it is constantly kept free from the dirt which the thread on touching the ring, 80 deposits on its top side.

A thread laying and piecing slit, *f*⁵, is provided in the ring *f*, and, in the builder plate, there is a corresponding slit *c*¹, while a disk *g*, secured to the spindle, has diametrically opposite slits *g*¹ and *g*². All of said slits are provided for the convenient and ready laying on, or piecing, of the yarn. The slits in the disk *g* hold the yarn so that the laying on can be effected while the spindle is running. A brake can be applied to the spindle at *k*. The slit *g*¹ is used when the spindle is rotating in the direction of the arrow *x* and the slit *g*² when the spindle is rotating in the opposite direction. The 90 top *f*⁶ of the slit *f*⁵ in the ring *f* is made with a portion *f*⁷ thinned off at one side as shown in the detail view at Fig. 5, while, at the bottom and opposite side of the slit, the portion *f*⁸ is likewise thinned off as shown in 100 Fig. 5 and, further, the slit *f*⁵ is also angled as shown at Fig. 1, these features being all designed to prevent the yarn catching at *y*¹ when running in the direction of the arrow *x* and at *y*² when running in the opposite direction. The angle of the slit also prevents centrifugal force acting on the end of the yarn and carrying it out of the ring *f* and it permits the yarn to drag on the inner wall or surface of the ring *f*.

In order 110 to prevent rust about the thread path a gunmetal or other rustless ring *h* is inserted

between the ring *f* and the builder plate *c*. The ring *h* could be reversed when worn at one side by the frictional contact of the ring *d*.

5. In addition to its anti-ballooning effect, the extension *f¹* of the ring *f* has the further advantage that it prevents spray being thrown out thereby conduced to greater cleanliness in the spinning operation.

10. Having now fully described my invention what I claim and desire to secure by Letters Patent is:—

15. 1. Ring spinning apparatus comprising a spindle, a slotted disk on said spindle, a builder plate, a movable ring, and a fixed ring of conoidal formation, said builder plate and said fixed ring having laying and piecing slits therein.

20. 2. Ring spinning apparatus comprising a spindle, a disk on the spindle having diametrically opposite slits therein, a builder plate having a straight slit therein, a movable

ring, and a fixed ring of conoidal formation having an angular slit therein.

3. Ring spinning apparatus comprising a 25 spindle, a slotted disk on said spindle, a builder plate, a movable ring, and a fixed ring of conoidal formation, said fixed ring and said builder plate having laying and piecing slits therein.

30. 4. Ring spinning apparatus comprising a spindle, a slotted disk on said spindle, a builder plate, an annular ring, and a fixed ring of conoidal formation provided with an annular recess for said ring, said builder plate and said fixed ring having laying and piecing slits therein.

In testimony whereof I affix my signature in presence of two witnesses.

WILLIAM GIBSON.
